UNITED STATES PATENT OFFICE.

JETHRO J. RICE, OF GRAND RAPIDS, MICHIGAN.

DESIGN FOR A SIDEBOARD, &c.

SPECIFICATION forming part of Design No. 23,925, dated January 1, 1895.

Application filed September 17, 1894. Serial No. 523,283. Term of patent 7 years.

To all whom it may concern:

Be it known that I, JETHRO J. RICE, a citizen of the United States, residing at Grand Rapids, in the county of Kent and State of Michigan, have invented and produced a new and original Design for Sideboards or Analogous Articles of Furniture, of which the following is a specification, reference being made to the accompanying drawing, in which the figure is a perspective view of a sideboard constructed in accordance with my design.

The leading feature of my design resides in a sideboard or analogous article of furniture the ends of the body of which are formed with or in what may be termed a triple curve, the two concave portions of which are at the front and rear of the said body and the convex portion intermediate.

In the drawing in which I have illustrated

my design in connection with a sideboard, the reference-numeral 1, indicates such a sideboard, the ends whereof are formed with or in a triple curve, the concave portions 2, 3 of which are disposed the one at the front and the other at the rear of the case, and the convex portion 4, of which is disposed intermediate the concave portions 2, 3. Ornamental borders 5 and 6, may be arranged at the top and bottom of the triple curved sides.

What I claim is—

The design for a sideboard or analogous article of furniture herein shown and described.

In witness whereof I have hereunto set my hand and seal in the presence of two witnesses.

JETHRO J. RICE. [L. S.]
